UNITED STATES PATENT OFFICE.

CHARLES M. MARKHAM, OF SAN DIEGO, CALIFORNIA.

LIFTING-JACK.

1,081,243.

Specification of Letters Patent.

Patented Dec. 9, 1913.

Application filed October 4, 1912. Serial No. 723,867.

To all whom it may concern:

Be it known that I, CHARLES M. MARKHAM, a citizen of the United States, residing at San Diego, in the county of San Diego and State of California, have invented an Improved Lifting-Jack, of which the following is a full and exact description.

My invention comprehends certain new and useful improvements in lifting-jacks, and is designed particularly for use in connection with girder supports for concrete construction forms, and the invention has for its object the provision of a supporting and lifting mechanism which will be simple, durable, and efficient for jacking up machinery, floor plates, beams, and the like, and which shall have no delicate or finely adjusted elements which would be likely to be affected by contact with, or clogged by accumulations of concrete, dust, or similar substances.

It is a design of the invention that the desired vertical adjustment may be quickly attained, that the elements of the device or mechanism shall be easily renewable, that the device shall be adapted for a quick release from the completed work or structure to which it has been applied, and that the parts of the device may be disassembled for convenience in packing.

For performing the functions herein set forth, the device may be embodied in a suitable form of mechanism, a preferred form of which is shown in the accompanying drawings, whereon—

Figure 1 is a side elevation of my device with the gripping levers partly in section; Fig. 2 is a side elevation of the device with the releasing levers and a portion of the bar which operates them; Fig. 3 is a plan and detail view of the rocker member having the release levers mounted thereon; and Fig. 4 is a transverse sectional and detail view of the rocker, disclosing the relative positions of the gripping lever, the releasing lever therefor, and the bar for operating the same.

In the several views, like reference characters apply to like parts.

My improved device has a standard 1, of steel pipe, having a base flange 2, and a table 3, on the opposite end, is provided with a movable member 4, slideable therein and extending from the standard. The table is provided with a rib 5, transversely arranged thereon, and adapted to engage with a cor-

respondingly grooved rib 6, on the bottom of rocker member 7. Bifurcated lugs 8 and 9, on opposite ends of the rocker, have links 10 and 11, respectively connected thereto, link member 10, being a relatively short, and link member 11, a relatively long link member. The said link members have pivoted thereto gripping levers 12 and 13 which have openings 14 and 15, extending obliquely therethrough. Loops 16, are adapted to receive a handle or operating bar 17, whereby an oscillating motion may be given to the rocker, and thereby cause the alternate release of gripping levers 12 and 13, which, upon their release, will drop down, and again grip the central movable member 4. While one gripping lever is lifting the central member on the upward motion of the corresponding end of the rocker, the opposite gripping lever is released to obtain a new grip on member 4. Links 18 connect the rocker to table member 3.

To lower the device with a weight or load on the support, rocker 7, has pivoted thereto releasing levers 19, having their inner extremities extending beneath gripping levers 12 and 13, and their outer extremities 20, extending from one side of the rocker. Loops 21, are adapted to carry operating bar 17, which normally rests lightly on levers 19, and by operating bar 17, their outer extremities 20, will be alternately depressed, causing the inner extremities to lift and release gripping levers 12 and 13, whereupon member 4 will be lowered. The lifting jack may be more quickly released by depressing the outer ends of the gripping levers. Central member 4 may have a plate 22, for carrying a load, and the plate may be modified for different uses.

From the foregoing it may be seen that I have provided a lifting jack which may be quickly adjusted and which has no parts which are liable to be affected by concrete. The oscillating motion of the rocker is effective for the intermittent and alternate release of the gripping levers, which, when so released, will drop down and obtain a new grip upon the central supporting member, and lift the same upon their upward movement. The lifting jack will lift heavy weights with but little friction as the several parts operate with an oscillating motion. The gripping tendency is increased in proportion to the weight or load carried. It will be apparent that I have provided an

2
improved device which may be advantageously employed in concrete construction, although it is not limited to any such use, but is susceptible of various other applications. The device is positive in action and affords considerable leverage so as to render necessary only a limited and minimum exertion on the part of the operator, the device also possessing the characteristics of simplicity, durability, and efficiency in construction and operation, and consisting of few parts cheaply manufactured and readily assembled.

I claim as my invention:

15 1. In a lifting jack, the combination with a standard having a base and a table member, of a rib extending transversely upon the table member, a rocker engaging with said rib, said rocker being adapted to oscillate upon said rib, loops on said rocker adapted to receive a detachable handle, bifurcated members mounted on opposite ends of said rocker, links pivotally connected to said bifurcated members, gripping levers connected to said links having a limited oscillating movement, a central supporting member slidably mounted in and extending from said standard and engaging with said gripping levers, and a handle adapted to be 30 inserted in said loops on the rocker for manually operating the device, substantially as set forth.

2. In a lifting jack the combination of a standard, a base on the lower end thereof, a 35 table on the top end, a rib extending transversely on said table, a rocker operating upon said rib, bifurcated members carried by the opposite ends of said rocker, links pivoted to said bifurcated members, loop gripping levers carried by said links and having an obliquely extending opening therein, means mounted on each end of said rocker engaging with said gripping levers for releasing same, a central member tele- 40 scopically mounted in said standard and extending therefrom and engaging with said gripping levers, and a handle mounted in loops on said rocker for manually operating said rocker.

3. In a lifting jack, the combination with 50 a standard having a flanged base member at the bottom and a flanged table member at the top, of a rib extending transversely on said table member, a rocker having a grooved bottom adapted to engage with said 55 rib and prevent lateral displacement of the rocker, loops on one side of said rocker adapted to receive the operating handle, a detachable handle adapted to be inserted in said loops and operate the rocker, bifurcated 60 members secured to opposite ends of said rocker, links pivotally connected to said bifurcated members, gripping levers pivotally connected to said links and adapted to a limited oscillating movement, said gripping 65 levers having obliquely disposed openings in their inner extremities, a central member slidably mounted in said standard and extending upward therefrom and through said openings in the gripping levers and normally engaging with the edges of said openings to lock said central member against a downward movement, and means for releasing said gripping levers comprising releasing 70 levers pivotally mounted on said rocker 75 and having their inner extremities extending upward and beneath said gripping levers and normally resting against them, the said releasing levers having their outer extremities projecting from a side of the rocker, 80 elongate loops on the same side of the rocker, and an operating lever adapted to be inserted in said elongate loops and normally rest upon the outer extremities of the releasing 85 levers, the said releasing levers alternately lifting and thereby disengaging said gripping levers from the central member when said operating lever is depressed to actuate the releasing levers, substantially as set forth.

90 In testimony whereof I have hereunto affixed my signature to the foregoing specification, this 28th day of September, in the year 1912.

CHARLES M. MARKHAM.
